UNITED STATES PATENT OFFICE

ALDEN B. LAWSON, OF BALTIMORE, MARYLAND

AIR PRESSURE WATER SYSTEM FOR PASSENGER CARS

Application filed January 17, 1930. Serial No. 421,551.

The present air pressure water system now in use on passenger railroad cars consists of a water tank secured to the under side of one side of a car, and equipped with a five way valve, strainers, governors, etc., for controlling air pressure that is taken away from the train line for supplying water to the car from this tank.

To fill the water tank in the system in vogue prior to my invention, it is necessary for trainmen to insert the water hose in the filling hole or inlet X, and then push down on handle Y which opens the five way valve Z permitting the water to flow through the pipe V and the strainer U into the tank W, and simultaneously with this action the five way valve automatically shuts off the air pressure from the water tank. This system permits the tank to be filled only from one side of the car. Therefore, if the car is in a train with its water tank on opposite side of car from the station hydrant, it introduces a hazard from a safety standpoint, in that it necessitates the terminal crew underneath the car, dragging the water hose over the rails, ballast, etc., to permit the filling of water tank. This is not only dangerous and unsanitary account of dragging the filling hose nozzle over rail and ballast, but also consumes considerable time, as the majority of stops at stations are limited to approximately 5 to 10 minutes, which makes it almost impossible for all tanks in an eight to ten car train to be filled before leaving time.

The object of my invention is to provide means in air pressure water systems for cars whereby the five way valve may be operated from either side of the car, and likewise to provide means whereby the water tank may be filled from either side of the car; and with these and other objects in view my invention consists of the parts and combination of parts as will be hereinafter pointed out.

In the drawings:

Figure 1 is a top plan view of part of an

air pressure water system embodying my invention.

Figure 2 is a front elevation of Figure 1 with an outline of car structure added.

Figure 3 is an enlarged detail view on the line 3—3, Figure 1.

Figure 4 is an enlarged detail end view of Figure 1.

Figure 5 is an enlarged detail view showing the connection between the rod and the operating handle.

The water tank, five way valve, filling or inlet, and supply pipe have been designated by reference letters as such parts thus described are in common use in water systems for cars.

In adapting the present water system for cars to embody my invention, I attach a water supply pipe 1 at one end to the water strainer U and extend said pipe to that side of the car opposite to the side on which the tank is mounted, the outer end of this pipe 1 being secured in the casting 2 constituting the filling or inlet on that side of the car. Thus it will be seen that the five way valve Z is connected with water supply pipes leading from both sides of the car, thus obviating the necessity of a member of the crew crawling under the car and dragging the hose with him, which fact by itself is of considerable moment both to the railroad company and the station crews because it entirely eliminates this hazard to life, saves time, and increases sanitation.

The five way valve Z is first operated to cut off air pressure to the water tank, and this is accomplished in my invention by operating the levers Y and 4 on either side of the car, said levers being mounted with a slip fit and clutch connection to the horizontally disposed shaft 5. This slip fit and clutch connection between the shaft 5 and the operating levers Y and 4 permits the shaft to be rotated from either side of the car, so that when operating the shaft from one side of the car it does not

move the lever on the opposite side of the car and hence liability of injury to persons by movement of the latter-named lever is avoided. It is, of course, understood that a system embodying my invention does not change the usual functioning of the five way valve and air attachments now used.

The slip fit and clutch connection referred to adapts each operating lever to be shifted 10 from an operative position, in which it is clutched to the shaft, to an inoperative position in which it is free from connection with the shaft and may be engaged with a fastener or retainer Y' on the adjacent side of the car, 15 whereby it may be held from movement in its inoperative position. The slip joint connection between the operating levers Y and 4 and the shaft 5 is made by forming a rectangular clutch portion 7 on the shaft 5 near 20 each end, which is designed to be interlocked in a rectangular clutch socket or opening 8 in the operating handle, each handle also being provided with a cylindrical opening 9 to receive that part of the shaft similarly 25 formed, so that the handle may be clutched to and unclutched from the shaft by shifting it longitudinally of the latter, and so that when the handle is free from connection with the shaft it may be swung up to engage its fastener or retainer Y'. To operate the shaft 5 either of the operating levers Y or 4 is released from its fastener or retainer and swung 30 from its inoperative position into its operative position and then pulled outwardly on the shaft until the rectangular opening 8 of the handle interlocks with the rectangular part of the shaft, whereupon a rotary motion of the operating lever rotates the shaft, which through the usual connections operates the five way valve cutting off the air and opening the tank for a supply of water.

In addition to elimination of the hazard above mentioned the use of my invention reduces the time required for filling tanks to 45 a minimum.

The shaft 5 is connected with the five way valve by link connections 10, the ends of which are pivotally connected to the arms 11 rigidly secured to the shaft 5 and the valve 50 Z, as clearly shown in Figure 4. A link connection 12 extends between the stem of the valve Z and the valve 13 on the drain pipe of strainer U which closes drain when levers Y and 4 are pushed down when filling tank 55 and opens drain when levers are up to release surplus water from pipes V and 1.

What I claim is:

1. In combination, in an air pressure water system for passenger cars, a water tank, an 60 inlet connection to said tank, a valve controlling the supply of water through said inlet connection to said tank, a water conduit extending from each side of the car to said valve device, a valve operating element, a 65 retainer at each side of the car, and a device

at each side of the car for operating said element, said device having a slip joint and clutch connection with said element whereby each operating device may be shifted from an operative to an inoperative position and vice versa, and engaged in its inoperative position with its retainer.

2. In combination, in an air pressure water supply system for passenger cars, a water inlet tank having an inlet connection, a valve controlling said connection, water supply pipes extending from opposite sides of the car to said valve, a valve operating rock shaft rotatably mounted in fixed bearings on the car, said shaft being operable for controlling the flow of water to the inlet connection from either pipe, a retainer at each side of the car, an operating device at each side of the car slidably mounted on the adjacent end of the shaft for movements between inoperative and operative positions, each operating device being engageable when in inoperative position with the retainer at its side of the car for holding it in such position, each shaft end and coating operating device having clutch surfaces for connecting the same when the operating device is released from its retainer and moved to its operative position.

3. In combination, in an air pressure water supply system for passenger cars, a water tank having an inlet connection, a water supply pipe extending to said connection from each side of the car, a valve controlling the supply of water from either pipe to the tank through the inlet connection, a valve actuating rock shaft extending from side to side of the car and journaled in fixed bearings thereon, a retainer at each side of the car, an operating device at each side of the car slidably mounted on the adjacent end of the shaft for adjustment to operative and inoperative positions, each operating device being engageable when in inoperative position with the retainer at its side of the car for holding it in such position, each shaft end and coating operating device having clutch surfaces engageable to connect the same when the operating device is released from its retainer and moved to its operative position, and crank arm and link connections between the rock shaft and the valve.

4. In combination, in an air pressure water supply system for passenger cars, a water tank having an inlet connection, a water supply pipe extending to said connection from each side of the car, a valve controlling the supply of water from either pipe to the tank through the inlet connection, a valve actuating rock shaft extending from side to side of the car and journaled in fixed bearings thereon, a retainer at each side of the car, an operating device at each side of the car slidably mounted on the adjacent end of the shaft for adjustment to operative and

inoperative positions, each operating device being engageable when in inoperative position with the retainer at its side of the car for holding it in such position, each shaft 5 end and coaxing operative device having clutch surfaces engageable to connect the same when the operating device is released from its retainer and moved to its operative position, crank arm and link connections between the rock shaft and the valve, and means 10 operative on each cut off motion of the valve for draining excess water from the pipe through which water has been supplied.

In testimony whereof I affix my signature.
